Primary Examiner — Cynthia Ramirez*Assistant Examiner* — Michael A Maharajh*(74) Attorney, Agent, or Firm* — Maschoff Brennan(57) **CLAIM**

The ornamental design for a wobbly toy ball, as shown and described.

DESCRIPTION

FIG. 1 is a front perspective view of a toy ball showing my new design;

FIG. 3 is a rear perspective view thereof;

FIG. 3 is a front side view thereof;

FIG. 4 is a rear side view thereof;

FIG. 5 is a left side view thereof;

FIG. 6 is a right view thereof;

FIG. 7 is a top view thereof; and,

FIG. 8 is a bottom view thereof.

The broken lines are for the purpose of illustrating portions of the wobble toy ball and form no part of the claimed design.
